WIRE MOUNTING INSULATOR

Richard J. Baatz, Edgerton, Minn., assignor of one-third
to Pawnee Corporation, a corporation of Minnesota

Filed Jan. 16, 1968, Ser. No. 10,185

Term of patent 14 years

U.S. Cl. D26—10
Int. Cl. D13—03

Fig. 1

Fig. 2

Fig. 3

Fig. 4

Fig. 5

Fig. 6

Fig. 7

FIG. 1 is a front perspective view of a wire mounting insulator showing my new design;

FIG. 2 is a top plan view thereof;

FIG. 3 is a bottom plan view thereof;

FIG. 4 is a front view thereof;

FIG. 5 is a rear view thereof;

FIG. 6 is a side view thereof taken from the left side of FIG. 4; and

FIG. 7 is a side view thereof taken from the right side of FIG. 4.

I claim:

The ornamental design for a wire mounting insulator, as shown.
